UNITED STATES PATENT OFFICE.

RYUSAI SAKAMOTO, OF TOKYO, JAPAN.

ELECTROSONATOR.

No. 900,429.

Specification of Letters Patent.

Patented Oct. 6, 1908.

Application filed April 11, 1907. Serial No. 367,492.

To all whom it may concern:

Be it known that I, RYUSAI SAKAMOTO, a subject of the Emperor of Japan, and residing at No. 25 Yanagi-cho, Ichigaya, Ushigome-ku, Tokyo, Japan, have invented new and useful Improvements in Electrosonators, of which the following is a full, clear, and exact description.

This invention relates to sound transmitters for transmitting sound into the human body to an internal organ.

The object of the invention is to provide a device in which the sound is produced by a vibrator operated from an electromagnet, the entire device being self-contained and readily held in the hand. By the use of this device, the examiner who listens through a stethoscope applied to the body adjacent the sound producer, may readily determine the exact position, form and motion of the internal organ of the body, as well as accurately determine any dislocation, enlargement or diseased condition.

Reference is to be had to the accompanying drawings forming a part of this specification, in which the figure shows a perspective view of my improved device, a portion thereof being broken away.

As shown, a wooden cylinder 33 carries at its end a frame formed of brass and including a ring 10 and two pairs of posts 14 and 16. The two posts 14 and 16 of each pair are connected together by transverse members 15, and the post 14 of one pair is connected to the post 16 of the other pair by a transverse member 13. The transverse members are each made up of two layers and the ends of the member 13 are preferably inserted between the separate layers of the member 15 above the posts 14. The members 15 serve as guides for a slide 13^a, which may be moved along the members 15 by a screw 12 having a head 11. At the outer end of the slide is a set screw 17, acting as a stop and having a lock nut 18 mounted thereon and adapted to engage with the upper surface of the slide.

Within the cylinder 33 is an electromagnet 30 formed by winding six or seven layers of insulated copper wire 29 about a core 28 formed of a body of iron wires. The electromagnet at its upper end is secured to the brass ring 9 on the outer cylinder to hold said magnet in position. The lower end of the cylinder 33 is closed by a threaded cap 1 screwed into a collar 3, and within the casing and beneath the electromagnet is any suit-

able form of storage battery. The battery is supported above the lower cap 1 by a coil spring 2, which also serves to electrically connect the lower metal cap 1 with the casing of the battery, which forms one of its electrodes. At the upper end of the storage battery, is a second coil 32, one end of which is connected to the central electrode of the storage battery and the other end of which is connected to one end of the wire forming the coil. The lower cap 1 is connected to a strip 5 extending along the length of the cylinder and in electrical contact with a longitudinally-movable slide 6. The slide may be operated by a suitable knob 7, and when forced upward may come into engagement with a contact or spring 8 carried by the collar 9 above referred to.

Mounted at one side of the outer cylinder, and extending beneath the stop 17, is a plate spring 20 serving as a vibrator. On the under surface of the plate is an armature 21 which may be drawn down upon the energizing of the electromagnet, and upon the outer surface is a small coating of platinum 19 which may come in contact with the lower end of the set screw or stop 17. Journaled on a pivot 26 at the outer end of the plate spring, is a brass rod 24 terminating in a ball 25 of insulating material, preferably, ebonite, and both the rod and the spring are supported from a brass plate 23, electrically connected to the upper end of the coil of the magnet or insulated from the remaining structure.

In using the device, the rod 24 is swung outward to a position substantially at right angles to the general direction of the length of the cylinder, and the slide 6 is moved up to contact with the spring 8. The current may then flow from the battery through the spring 2, casing 1, strip 5, slide 6, spring 8, to the posts of the frame, and thence to the set screw 17. From here the current flows through the plate spring to the plate 23 and thence through the electromagnet back to the battery. The action of the magnet draws down the electrode 21 to break the connection at the lower end of the stop or set screw 17; and this breaking of the circuit de-energizes the magnet and permits the spring and armature to return, and the operation is repeated. The current is thus repeatedly interrupted and the plate spring vibrates rapidly, making a buzzing sound as long as the slide 6 is held in engagement with the spring 8. The vibration of the plate spring will be

transmitted to the ebonite ball 25 through the medium of the brass rod 24, and the ebonite ball is held in contact with the human body adjacent the organ which it is desired 5 to examine. The pitch of the vibrator may be varied by turning the screw 12 to vary the point of contact between the vibrator and the stop 17, and the extent of vibration may be varied by rotating the stop. The head 11 10 on the screw 12 may, if desired, be formed of celluloid, and may constitute the portion held in engagement with the body.

In using my improved apparatus, the cylinder 33 is held in one hand and the button 7 15 is moved upwardly by means of the thumb, to bring the slide 6 into engagement with the receiver 8. This closes the electric circuit and the plate spring 20 begins to vibrate. A stethoscope of any suitable character is 20 held in the other hand and applied to the portion of the body to be examined. The terminal ball 25 of my improved apparatus is moved about over the surface of the body being examined, and the examiner listens 25 through the stethoscope to distinguish variations in the sound, as the latter is transmitted from the apparatus through the body to the stethoscope. In examining an internal organ, it will be noted that a marked 30 difference in the sound is noticeable, as the ball passes beyond the margin of the organ. Thus, the shape, size and exact location of the organ may be readily determined.

By means of my improved apparatus, I 35 produce a musical sound of uniform and constant pitch and wave length and capable of being maintained for a long time. The extent of the vibration may be varied for examination of different organs.

40 The construction of the apparatus is very

simple, its manipulation easy, and the part which touches the body is small so that it may be used upon all portions of the body. No perceptive pain or disagreeable feeling is felt by contact with the skin.

45

Having now particularly described and ascertained the nature of my said invention and in what manner the same is to be performed I declare that what I claim is:—

1. A device of the class described, comprising a casing, an electromagnet, and a battery mounted within said casing, an electric plate spring mounted on said casing adjacent said electromagnet, a frame carried by said casing and disposed adjacent said plate spring, a regulating screw mounted in said frame for engagement with said spring to limit the movement thereof, and means for moving said regulating screw laterally to vary its point of contact on the spring. 50

2. A device of the class described, comprising a casing, an electromagnet, and a battery mounted within said casing, an electric plate spring mounted on said casing adjacent said electromagnet, a frame carried by 55 said casing and disposed adjacent said plate spring, a regulating screw mounted in said frame for engagement with said spring to limit the movement thereof, and a slide carried upon one side of said casing and movable longitudinally for closing the circuit through said plate spring. 60

65 In testimony whereof I have hereto signed my name in the presence of two subscribing witnesses.

RYUSAI SAKAMOTO.
